91,711

DESIGN FOR AN AUTOMOBILE

Oswald M. Gross, Detroit, Mich.

Application January 25, 1934, Serial No. 50,510

Term of patent 14 years

To all whom it may concern:

Be it known that I, OSWALD M. GROSS, a citizen of the United States, residing at Detroit, in the county of Wayne and State of Michigan, have invented a new, original, and ornamental Design for Automobile, as shown in the accompanying drawings and described in the following specification.

I claim:
The ornamental design for an automobile as shown.

OSWALD M. GROSS.
